UNITED STATES PATENT OFFICE.

ALEXANDER TWAROGOWSKI AND STANISLAW KLOSINSKI, OF DETROIT, MICHIGAN.

ROTARY HEEL.

1,377,642.

Specification of Letters Patent. Patented May 10, 1921.

Application filed September 29, 1920. Serial No. 413,568.

To all whom it may concern:

Be it known that I, ALEXANDER TWAROGOWSKI, a citizen of the United States, residing at Detroit, county of Wayne, and State of Michigan, and I, STANISLAW KLOSINSKI, a citizen of the United States, residing at Detroit, county of Wayne, and State of Michigan, have invented certain new and useful Improvements in Rotary Heels, of which the following is a specification.

This invention relates to improvements in foot wear and particularly to improvements in the heels for boots and shoes.

15 It is the principal object of the invention to provide a heel-plate or plug which is readily attachable to or removable from an ordinary heel and which is held thereon interchangeably and against displacement.

20 A further object of the invention is the provision of a heel-plate which can be locked in its adjusted position and which may be turned in order to present a new wearing edge to the ground, if for instance it is worn off faster at one side than the other, and which can be locked in this position.

25 A still further object of the invention is the provision of a heel-plate which can be lowered somewhat or within certain limits in its entirety, if the general wear of the heel should this require, and which may be locked in any of its positions.

These and other like objects are attained 30 by the novel construction and combination of parts hereinafter more fully described and so forth in the appended claims.

In the accompanying drawing forming a material part of this disclosure—

40 Figure 1 is a fragmentary side view showing a conventional type of shoe with the heel-plate according to the present invention attached thereto.

Fig. 2 is a top plan view of the heel-plate taken along line 2—2 of Fig. 1.

45 Fig. 3 is a section along line 3—3 of Fig. 2.

Fig. 4 is a rear end view of the heel-plate.

50 Fig. 5 is a bottom view of the heel-plate seen in the direction of the arrow, Fig. 4.

Referring in detail to the drawing, a shoe 10 of the conventional type has a heel part 11 and a sole 12, as customary. The heel part may be composed of a number of the usual lifts.

To this heel part 11 a heel-plate, generally

indicated at 13, is attached by means of screws or the like 14 preferably 6 in number (Fig. 3). This plate 13 has an upstanding marginal flange 15 and within the space or area limited by this flange at the front part of the heel, a chamber, 15' is provided which is filled by a rubber cushion 16 of peculiar formation, as indicated in Fig. 5, which is held within the plate by any desired means for instance a cement or the like, and the lower face of which is flush with the bottom face of the plate.

The rear part of the heel-plate is formed by a solid body 17 integrally made with the metal of the plate and provided with a central screw-threaded opening 18 for the reception of the threaded outer face of the stem 19 of a plate 20 to which is secured by means of screws 21 or the like a rubber cushion 22 of circular configuration which on its underside shows a circular or central depression 23 provided with a central opening 24 through which the bit of a screw-driver or similar tool may be introduced. The upper part of the stem 19 carries a metallic spider 25, as shown in Fig. 2, which is provided in its outer periphery with recesses 26, while between two ridges 27 and 28 to both sides of its center, a bore or hole 29 is arranged for the reception of a screw, the head of which is located within the hollow space of the stem 19, so that it can be engaged by the bit of a screw-driver etc. introduced through the opening 24 and the opening 32 in the center of the plate 20.

Any of the recesses 26 is adapted to be engaged by the inner end of a locking member 33, the outer end of which is passed through the cushion 16 and the flange 15 at its rear face and carries a pin or the like manipulating member 34. Between the inner wall of the cushion 16, and the outer wall of the stem 19 a spring 35 is wound or coiled around the member 33.

When in use, the heel-plate 13 is attached to the heel by means of the screws 14 preferably 6 in number and the plug 22 with its plate 20 and stem 19 is secured in its place within the opening 18 by means of a screw driver, while the end of the locking member 33 engages one of the recesses 26. If the plug or cushion 22 has become worn more on one side, than on the other, it may be turned by a screw-driver introduced through 24 after the locking member 33 has been withdrawn out of its engagement with

one of the recesses 26. The recesses 26 are deep enough to allow the entire plug or cushion 22, when worn off to be lowered and locked in its lowered position by means of 5 the locking member 33 without the danger of losing the entire cushion.

Having thus described our invention, what we claim as new and desire to secure by Letters Patent of the United States is—

- 10 1. In a device of the character described, a heel-plate adapted to be secured to a shoe heel, and having an annular central cavity in its rear body and a rubber cushion in its chambered front part, a metallic plate having a stem screwed into said cavity, a rubber cushion secured to said metallic plate, a recessed spider at the upper end of said stem, and means engaging in the recess of said spider for locking the parts in their relative adjusted positions.
- 15 2. In a device of the character described, a heel-plate adapted to be secured to a shoe heel, an upstanding marginal flange on said plate, a chamber formed in the front end 25 of said plate, a rubber cushion secured in said chamber, a solid body forming the rear part of said plate and having an annular central cavity formed by screw-threaded walls, a metallic plate having a screw threaded stem secured in said cavity, a rubber cushion having a central depression and a central opening secured to said plate, a 30 spider on said stem provided with marginal recesses, means for securing said spider to a shoe heel, and means engaging the recesses in said spider for locking the parts in their relative adjusted positions.
- 35

3. In a device of the character described, a heel-plate adapted to be secured with its upper face to the heel of an article of foot wear, and an upstanding marginal flange on said plate, a chamber limited by said flange formed in the front part of said plate, a solid rubber cushion secured in said chamber, a solid body formed with the rear part 45 of said plate and having an annular central bore provided with screw-threaded walls, a metallic plate having a central opening and a hollow screw threaded stem adapted to be threaded into the bore of said solid body, 50 a circular rubber cushion adapted to be secured to the underside of said metallic plate, and having a central depression and a central hole in alignment with the opening of said metallic plate, a spider formed at the 55 top of said stem having a plurality of marginal recesses, two central ridges formed with said spider, and a central opening adapted to receive a screw formed in the middle of the spider between said ridges, a 60 locking member engaging with its inner end any of the recesses of said spider and passed through the cushion and the rear flange, an operating ring at the extreme outer end of said member, and a spring coiled around 65 said member between said cushion and said stem for normally locking the parts against displacement in their relative adjusted positions.

In testimony whereof we have affixed our 70 signatures.

ALEXANDER TWAROGOWSKI.
STANISLAW KLOSINSKI.
